(57) **CLAIM**

The ornamental design for a rectangular scraper, as shown and described.

DESCRIPTION

FIG. 1 is a perspective view of the rectangular scraper of our new design;

FIG. 2 is a top plan view of the rectangular scraper of our new design;

FIG. 3 is a bottom plan view of the rectangular scraper of our new design;

FIG. 4 is a side elevational view of the right side of the rectangular scraper of our new design;

FIG. 5 is a side elevational view of the left side of the rectangular scraper of our new design;

FIG. 6 is an enlarged front elevational view of the rectangular scraper of our new design; and,

FIG. 7 is an enlarged rear elevational view of the rectangular scraper of our new design.

The broken line showing of the scraper head and the fasteners in FIGS. 1 to 7 depicts environment and forms no part of the claimed design.

1 Claim, 4 Drawing Sheets
